DISPLAY DEVICE

John E. Dunphy, Boston, and John S. Mulvey,
Acton, Mass.

Application September 7, 1949, Serial No. 4,892

Term of patent 14 years

(Cl. D80—9)

To all whom it may concern:

Be it known that we, John E. Dunphy and John S. Mulvey, citizens of the United States of America, and residents of Boston, county of Suffolk, and Acton, county of Middlesex, Commonwealth of Massachusetts, respectively, have invented a new, original, and ornamental Design for Display Device, of which the following is a specification, reference being had to the accompanying drawing, forming part thereof.

In the drawing:

Fig. 1 is a side elevation of a display device, showing our new design.

Fig. 2 is a top view thereof.

Fig. 3 is a bottom plan view thereof on a reduced scale.

We claim:

The ornamental design for a display device, substantially as shown.

JOHN E. DUNPHY.
JOHN S. MULVEY.
